UNITED STATES PATENT OFFICE.

JAMES W. BRYCE, OF BINGHAMTON, NEW YORK, ASSIGNOR TO INTERNATIONAL TIME RECORDING COMPANY, OF NEW YORK, A CORPORATION OF NEW YORK.

SYNCHRONIZING CLOCK SYSTEM.

1,310,788.

Specification of Letters Patent. Patented July 22, 1919.

Application filed November 16, 1918. Serial No. 262,757.

To all whom it may concern:

Be it known that I, JAMES W. BRYCE, a citizen of the United States, residing at Binghamton, in the county of Broome and State of New York, have invented certain new and useful Improvements in Synchronizing Clock Systems, of which the following is a full, clear, and exact description.

In an application filed by me on May 21, 1918, Serial Number 235,813, I have set forth and described a new method and apparatus for controlling and synchronizing a plurality of secondary clocks by means of a master clock, and this application is for an improvement on such systems.

In the original system as set forth in the application above referred to the master clock, in addition to its other functions connected to a controlling or line circuit at definite intervals of predetermined duration a source of continuous current. Each secondary clock was equipped with means for retarding and means for accelerating its rate, and two circuit-closers operated by the secondary clock movement for definite periods in fixed relation to the time as indicated by its hands to connect to line either the one or the other means, whereby, when any portion of such periods overlapped in time the period during which the master clock sent its current over the same line, this current would pass to and operate the retarding means if the clock were too fast, or the accelerating means, if it were too slow, and thus bring the secondary into exact synchronism with the master clock.

In some systems the master and secondary clocks are wound, when necessary, by hand, in others the secondaries are periodically or continuously wound by current impulses under the control of the master clock, while in still others the secondary clocks are operated by momentary periodic impulses sent over the line by the master clock, for example, once a minute. These latter are known as impulse systems and it is to them that this invention relates.

Ordinarily in such systems the transmitted impulses are all in the same direction, or their direction is immaterial so far as their operative effect is concerned, but in the present case the synchronizing of the secondary clocks is effected through suitable instrumentalities by a change in the direction of flow of such impulses, and the man-

ner in which I accomplish this may be thus generally described.

It may be assumed that for a given but arbitrary interval, say from the hour to forty-five minutes past the hour, the master clock sends positive current impulses to line and for the remaining fifteen minutes of each hour negative current impulses. All of these impulses actuate alike the secondary clock-driving mechanism, and are presumed to keep it on time.

Each secondary, however, is provided with means for retarding and with means for accelerating its rate, and with two circuit-controllers which are operated by the clock to bring into operative relation to the line either of said means for definite intervals in fixed relation to the time as indicated by the hands of the secondary clocks. If the clock be on time such periods will not overlap in time the period of reverse or negative impulses from the master clock and no effect is produced, but should any portion of either of such periods overlap that of the negative current, then by means of devices responsive to such negative currents the retarding device is brought into action if the secondary be too fast, or the accelerating device if it be too slow, until the condition of exact synchronism is reestablished.

This system is illustrated in the accompanying drawing in which Figure 1 is a diagram of the complete system, and Fig. 2 a sectional view of a differential gear used in a secondary clock.

The master clock may be of any known construction and comprises a driving train 1, a verge shaft 2, carrying a contact 3, and a minute shaft 4 having an arm 5 with which the oscillating contact 3 engages once each minute. On the hour shaft 6 is a disk 7 having two conducting segments 8, 9, set in its periphery, and upon such periphery bear two closely placed brushes or strips 10.

By the operation of the clock, the segment 8 comes under the brushes at exactly fifteen minutes of the hour, and the segment 9 under the said brushes at the even hour. From this it will result that when the brushes are on segment 8 an impulse of current flows from any suitable local source 11, through the contact 3 and an electro-magnet 12, which operates to move a ratchet wheel 13 one step, and to thereby shift to the right an insulating rod 14 supported by two

spring contact arms 15 of a circuit controller. At the even hour, when brushes 10 lie over the segment 9, another impulse is sent through magnet 12, the ratchet 13 moved another step and the rod or bar 14 drops to the left between the adjacent ratchet teeth.

The movement of the contacts 15 thus obtained, connects, say the positive wire 16 of a source of direct current to either line wire 17 or line wire 18, the usual and ordinary means depending upon the position of the contacts 15, being employed for this purpose.

15 It will be observed that contact 3 comes into engagement with the arm 9 once each minute, and this is utilized to send from the source 12 a current impulse over a wire 19 which includes a relay magnet 20, which 20 being thus energized attracts its armature 21 and closes a break in the main or controlling circuit 17, 18, sending thereby the impulses either positive or negative, as the case may be, that operate the secondary 25 clocks.

In general, therefore, it will be seen that the master clock sends a current impulse to line once each minute, which impulses operate the hands of the secondary clocks, and 30 that from the hour to forty-five minutes after the hour these impulses are say positive, while for the remaining fifteen minutes of each hour they are negative.

In the secondary clock, which is shown 35 at the right of Fig. 1, the minute arm 22 is fixed to the post or bar 23 of the floating member of a differential gear. One of the gear members of this device 24 is fast to a hub 25, loose on the shaft 22, and the other 40 26 is fast to a similar hub 27. The hub 25 carries a ratchet wheel 28 which is moved step by step by a pawl 29 operated by the impulses transmitted over the line which pass through one of the opposing coils 30 45 of a relay. Assuming the hub 27 to be stationary, the floating member 23 of the differential is therefore rotated and carries with it the minute arbor of the clock.

The hub 27 carries a ratchet wheel 31 with 50 which engages a long throw pawl 32 operated by a magnet or solenoid 33 and adapted by the energization of such solenoid to be turned in a direction opposite to the normal movement of the ratchet 28.

55 The hour shaft of the secondary clock carries a cam disk 34 which operates to shift a spring contact 35. At thirty minutes of the hour as indicated by the hands of the secondary clock the contact 35 is forced by 60 the high part of the cam into engagement with a contact 36 and closes a circuit from the stop 37 of a polarized relay 38, through the solenoid 33 and back to line wire 17. This engagement continues until fifteen 65 minutes of the hour, as indicated by the

hands of the secondary clock, when the contact 35 drops onto a lower portion of the cam disk and interrupts this circuit.

If the impulses transmitted over the line are positive the armature 39 of the relay 70 is repelled, and the circuit including contacts 35, 36 and solenoid 33 is not closed. If therefore the secondary clock be on time the reversal of the direction of flow of the line impulses produces no effect on the sole- 75 noid 33, for at the instant of change the contact 35 has dropped off of the high part of the cam. Should the secondary be slow, however, then the engagement of contacts 35 and 36 is not interrupted until after the 80 the instant when the direction of the line impulses changes, in which event the armature 39 being attracted, current is directed from the line through the solenoid 33, and the ratchet wheel 31 is thereby 85 turned sufficiently to bring the secondary clock up to synchronism with the master clock when the contacts 35 and 36 will instantly separate.

At exactly the hour the cam 34 permits 90 the contact 35 to drop onto a contact 40 and if the clock be too fast this will occur before the change in the line impulses from negative to positive has taken place. Hence the line current will flow from the stop 37 95 through contacts 35 and 40 and through the second of the two opposing coils 41 of the relay, and back to line, and this impulse will neutralize the magnetizing effect of the line impulse and the relay will not operate 100 its pawl 29, nor move the clock until the master clock has reversed the line impulses at the even hour. By this means the secondary clock is brought into synchronism.

In illustrating the invention I have 105 shown specific devices for stopping the clock and for advancing its hands by one operation, but these are broadly typical of any means for retarding or for accelerating its rate of movement that may be used. In 110 other respects the invention is not limited to the special means shown and described.

Having now described my invention, what I claim is:

1. In a synchronizing clock system the 115 combination with a master clock adapted to send for predetermined intervals of definite duration current impulses of given direction over the line for the operation of secondary clocks, of one or more secondary clocks each 120 containing means for retarding and means for accelerating its rate of movement, two circuit controllers which bring said means into operative relation to the line circuit at definite intervals in fixed relation to the 125 time as indicated by the hands of the secondary clock, and means dependent upon the direction of the impulses over the line for connecting said line circuit with either the means for retarding or with the means 130

for accelerating the secondary clock, whereby the latter if out of synchronism with the master clock will be retarded if too fast or accelerated if too slow.

- 5 2. In a synchronizing clock system the combination with a master clock adapted to send for predetermined parts of given periods positive impulses and for the remaining parts of such periods negative impulses
10 to line for the operation of one or more secondary clocks, means in each for retarding and means for accelerating their rate of movement, circuits including said means, circuit controllers for completing breaks in
15 such circuits at definite intervals in fixed

relation to the time as indicated by the hands of the secondary clocks, a polarized relay in the main line and connections between the main line and the retarding and accelerating circuits in the secondary clock, 20 whereby on the transmission of impulses in one direction the main line will be connected to either the retarding or the accelerating means and the secondary clock, if it be too fast or too slow, brought into synchronism 25 with the master clock.

In testimony whereof I hereunto affix my signature.

JAMES W. BRYCE.
